UNITED STATES PATENT OFFICE.

CHARLES H. PALMER, JR., OF MERRIMAC, MASSACHUSETTS.

DESIGN FOR A CARRIAGE-BODY.

SPECIFICATION forming part of Design No. 12,275, dated May 24, 1881.

Application filed April 14, 1881. Term of patent 3½ years.

To all whom it may concern:

Be it known that I, CHARLES H. PALMER, Jr., a citizen of the United States, residing at Merrimac, in the county of Essex and State of Massachusetts, have invented and produced a new and original Design for a Carriage-Body, of which the following is a specification, reference being had to the accompanying photograph, forming part thereof.

10 The photograph represents my newly-designed carriage-body in side elevation.

In my new design the side portion of the body opposite the ends of the seat and back is composed of a panel, A, which extends from 15 the line of the bottom of the box e upward above the level of and to serve as sides or arms for the seat, the said panel being curved at front and back. The top edge of the panel is curved or inclined upward from its front to its rear 20 edge, as at c, and the bottom or lower edge of the panel is straight. The side of the carriage-box e is shown as extended backward at the rear of the lower end of the panel A, the lower 25 part of the box being in line with the lower end of the panel, while that part of foot part marked f in front of the seat and panel A is

curved or concaved or extended downward, forward, and upward in continuation of the front end, a, of the panel.

The leading feature of my design consists in 30 the panel extending from the line of the bottom of the box upward above the line occupied by the seat.

I claim—

1. The design for carriage-body herein shown 35 and described, it consisting of the panel A, with the box part e extended across the said box, and terminating at its lower end in the line of the bottom of the box, as shown.

2. The design for carriage-body as herein de- 40 scribed, it consisting of the panel A, box e, ex- tended backward from one end thereof, and the curved foot part extended downward, forward, and upward from the front of the panel, as shown and described.

In testimony whereof I have signed my name to this specification in the presence of two sub-scribing witnesses.

CHARLES H. PALMER, JR.
